Des. 234,151
Patented Jan. 21, 1975

234,151

SPINNER TOY

Lloyd E. Cross, Jr., Troy, Kans. 66087
Filed Aug. 3, 1972, Ser. No. 277,796

Term of patent 3½ years

Int. Cl. D21—01
U.S. Cl. D34—15 AA

FIGURE 1

FIGURE 2

FIGURE 3

FIGURE 4

FIGURE 5

FIGURE 6

FIG. 1 is a perspective view of the spinner toy embodying my new design;

FIG. 2 is a top plan view thereof;

FIG. 3 is a side elevational view thereof, the side opposite being substantially identical;

FIG. 4 is a bottom plan view thereof;

FIG. 5 is a front elevational view thereof;

FIG. 6 is a rear elevational view thereof.

I claim:

The ornamental design for a spinner toy, as shown and described.
